CLAIM

I claim the ornamental design for a tourniquet buckle, as shown and described.

DESCRIPTION

FIG. 1 is an isometric view showing a tourniquet buckle in accordance with my new design, shown attached to a portion of a tourniquet;

FIG. 2 is a plan view of the buckle of FIG. 1;

FIG. 3 is bottom view of the buckle of FIG. 1;

FIG. 4 is a right side view thereof; and

FIG. 5 is a left side view.

FIG. 6 is front elevation of the buckle of FIG. 1;

FIG. 7 is rear elevation of the buckle of FIG. 1;

FIG. 8 is an enlarged top view of the buckle of FIG. 1, without the attached tourniquet;

FIG. 9 is an enlarged bottom view of the buckle of FIG. 1, without the attached tourniquet;

FIG. 10 is a cross sectional view taken along the lines 10-10 of the buckle of FIG. 8;

FIG. 11 is a cross sectional view taken along the lines 11-11 of the buckle of FIG. 8;

FIG. 12 is a cross sectional view taken along the lines 12-12 of the buckle of FIG. 8; and,

FIG. 13 is a cross sectional view taken along the lines 13-13 of the buckle of FIG. 8.

In the drawings, the broken lines are for the purpose of illustrating portions of the tourniquet buckle that form no part of the claimed design.
